United States Patent Office

Des. 196,105
Patented Aug. 27, 1963

196,105

BUMPER

Lucien Pera, Billancourt, France, assignor to Regie
 Nationale des Usines Renault, Billancourt, France

Filed July 6, 1961, Ser. No. 65,825

Claims priority, application France Jan. 16, 1961

Term of patent 14 years

(Cl. D14—6)

FIG. 3.

FIG. 4.

FIG. 1 is a front perspective view of the bumper, showing my new design;

FIG. 2 is a front perspective view thereof in extended position;

FIG. 3 is a side perspective view thereof in closed position;

FIG. 4 is a side perspective view thereof in extended position.

The characteristic features of my design reside in the vertical combination bumper and bracket bars, as shown.

I claim:

The ornamental design for a bumper, as shown and described.
